VALVE FOR ROCK DRILLS

Filed Sept. 28, 1928

FIG.-1.

INVENTOR.
Albert R Mack
BY *John A. P. Jr.*
HIS ATTORNEY

UNITED STATES PATENT OFFICE

ALBERT R. MACK, OF EASTON, PENNSYLVANIA, ASSIGNOR TO INGERSOLL-RAND COMPANY, OF JERSEY CITY, NEW JERSEY, A CORPORATION OF NEW JERSEY

VALVE FOR ROCK DRILLS

Application filed September 28, 1928. Serial No. 309,101.

This invention relates to rock drills, but more particularly to a current thrown distributing valve for fluid actuated rock drills of the hammer type.

5 The objects of the invention are to obtain a rapid distribution of pressure fluid to the ends of the cylinder and to assure against leakage of pressure fluid from the valve chamber into the cylinder in advance of the 10 piston, thus enabling the piston to deliver a heavy blow against the working implement which it is adapted to actuate.

Other objects will be in part obvious and in part pointed out hereinafter.

15 In the drawings illustrating a practical application of the invention and in which similar reference characters refer to similar parts,

Figure 1 is a sectional elevation of a portion of a rock drill having the invention applied thereto,

Figure 2 is a transverse view taken through Figure 1 on the line 2-2 looking in the direction indicated by the arrows, and

25 Figure 3 is a perspective view of the valve.

Referring more particularly to the drawings, A designates generally a rock drill and B a cylinder in which is formed a piston chamber C. The cylinder B is provided with 30 free exhaust ports D which are controlled by a piston E reciprocable in the piston chamber C.

A closure is provided for the front end of the piston chamber C in the form of a front 35 cylinder washer F having a bore G to slidably receive an extension H of the piston E. In the rearward end of the cylinder B is an enlarged bore J to receive, among other elements, a back cylinder washer K which forms 40 a closure for the rearward end of the piston chamber C.

The drill A is provided with a back head L which is disposed at the back end of the cylinder B and may be secured thereto in 45 any suitable manner, as for instance, by the usual side rods (not shown). In the present instance the back head L serves as a housing for a throttle valve O disposed in a throttle valve chamber P in the back head. The throttle valve O has a lever Q whereby it may be

rotated and in this instance has a central chamber R which may be in constant communication with a source of pressure fluid supply. In the wall of the throttle valve O is a port S through which pressure fluid may 55 flow from the chamber P into a passage T leading to a supply reservoir U in the front end of the back head L.

In accordance with the present invention, means are provided for effecting the distribution of pressure fluid to the ends of the piston chamber C for actuating the piston E. To this end the drill A is provided with a valve mechanism designated generally by V and disposed in the bore J between the back cylinder washer K and the back head L. The valve mechanism V comprises in this instance a valve chest W in the form of a plate having a rectangular aperture to form a valve chamber X and on the rearward end of the valve chest W is seated a plate Y to form a closure for the rearward end of the valve chamber X and also to form a seat for the back head L. 60

70 In the form of the construction shown the rearward surface Z of the back cylinder washer K serves as a valve seat and in the back cylinder washer K is formed an inlet passage b which leads from the valve chamber X to the rearward end of the piston chamber C. Similarly a front inlet passage c is formed in the back cylinder washer K and in the cylinder B to convey pressure fluid from the valve chamber X to the front end of the piston chamber C. The valve chamber X is constantly exposed at both ends to pressure fluid and such pressure fluid is conveyed thereto through supply ports d and e in the plate Y. The supply ports d and e are preferably located so that they open into the valve chamber X at or near its ends. 75

80 The distribution of pressure fluid from the valve chamber X to the ends of the piston chamber C is effected by a distributing valve f slidable in the valve chamber X. The distributing valve f is preferably of rectangular conformation and in this instance comprises a dome g, the upper surface h of which is adapted to cooperate slidably with the plate Y for preventing leakage of pressure fluid 85 90 95 100

from one side of the valve chamber X to the other at this point.

The sides *j* and *k* of the dome *g* constitute actuating or throwing surfaces against which pressure fluid acts for throwing the valve *f* from one limiting position to the other. Adjacent the actuating surfaces *j* and *k* are lateral flanges *o* and *p* and said flanges are adapted to slide on the surface *Z* of the back cylinder washer *K* and over the inlet passages *b* and *c* for controlling the admission of pressure fluid into the piston chamber. In the present instance the ends *q* and *r* of the flanges *o* and *p* respectively also serve 15 as actuating surfaces against which pressure fluid may act for throwing the valve.

By providing the valve *f* with the lateral flanges *o* and *p*, pressure surfaces *s* and *t* are formed on the rearward ends or sides 20 of the flange against which pressure fluid may constantly act tending to press the valve firmly on the surface *Z*. This is desirable since it insures against leakage of pressure fluid into the ends of the piston chamber *C* and thus prevents short stroking or the 25 delivering of a weak blow of the piston *E* due to the presence of pressure fluid leaking to the end of the piston chamber *C* towards which the piston *E* is travelling.

In order to maintain the weight of the 30 valve *f* to a minimum said valve is provided with a transverse groove or recess *u* which may extend from one side of the valve to the other. In the present instance this recess *u* is utilized as a means for stopping the valve 35 in its limiting positions so that the actuating surfaces *q* and *r* will be held free of contact from the ends of the valve chamber. Accordingly a pin *v* is seated in the back cylinder washer *K* and extends into the recess *u* to cooperate with the walls of said recess 40 for stopping the valve.

The operation of the device is as follows: With the throttle valve *O* in the open position, 45 pressure fluid will flow from the chamber *R* through the passages *T* into the supply reservoir *U*. From thence the pressure fluid will flow through the supply ports *d* and *e* into the ends of the valve chamber *X*. With the valve *f* in the position illustrated 50 in the drawings, the front inlet passage *c* will be covered by the flange *o* and the inlet passage *b* will be uncovered so that pressure fluid will flow from the valve chamber *X* 55 through the inlet passage *b* into the rearward end of the piston chamber *C* to actuate the piston *E* forwardly in the direction of the working implement.

As the piston *E* advances in a forwardly 60 direction, the exhaust port or ports *D* will be uncovered thereby to permit the escape of the pressure fluid from the rearward end of the piston chamber *C* to the atmosphere. When this exhaust of pressure fluid occurs 65 from the rearward end of the piston chamber,

there will be a substantial drop in the pressure fluid acting against the surfaces *k* and *r* of the valve. The pressure fluid acting against the surfaces *j* and *q* on the opposite side of the valve *f* being equal to line pressure will therefore be of sufficient value to overcome the reduced pressure acting against the surfaces *k* and *r*. The valve *f* will then be thrown to its other extreme position and the inlet passage *b* will then be covered by the flange *p* and the inlet passage *c* will be 70 uncovered by the flange *o*.

In the new position of the valve, pressure fluid will flow through the inlet passage *c* into the piston chamber *C* and will impel the piston rearwardly. As the piston *E* approaches the rearward end of the piston chamber *C*, the exhaust ports *D* will be uncovered and consequently, there will be a 75 decided drop in the pressure fluid existing in that end of the valve chamber *X* through which pressure fluid has passed into the cylinder. The valve *f* will then again be in a state of unbalance and the pressure fluid acting against the surfaces *k* and *r* will return 80 the valve to its initial position.

From the foregoing description, it will readily be seen that the pressure fluid acting on the surfaces *s* and *t* of the flanges *o* and *p* will at all times tend to press the valve *f* 85 firmly against the surface *Z* of the back cylinder washer *K* in any of the positions which the valve may assume in the valve chamber. In this way the inlet passages *b* and *c* may be 90 properly closed and there will therefore be no leakage of pressure fluid from the valve chamber into the ends of the piston chamber towards which the piston *E* is moving.

I claim:

1. In a fluid actuated rock drill, the combination of a cylinder and a piston, a free exhaust port in the cylinder controlled by the piston, a valve chest having a rectangular valve chamber, inlet passages leading from the valve chamber to the cylinder, a pressure actuated distributing valve in the valve chamber having flanges slidable over the inlet passages for controlling the admission of pressure fluid into the cylinder, and supply ports in the valve chest to admit pressure fluid into the ends of the valve chamber for actuating the valve and for supplying the inlet passages.

2. In a fluid actuated rock drill, the combination of a cylinder and a piston, a free exhaust port in the cylinder controlled by the piston, a valve chest having a rectangular valve chamber, inlet passages leading from the valve chamber to the cylinder, a pressure actuated distributing valve in the valve chamber having flanges slidable over the inlet passages for controlling the admission of pressure fluid into the cylinder, said flanges being constantly exposed to pressure fluid on one side for holding the valve seated 125 130 135 140 145 150

in the valve chamber, and supply ports in the valve chest to convey pressure fluid into the ends of the valve chamber for actuating the valve and for supplying the inlet passages.

- 5 3. In a fluid actuated rock drill, the combination of a cylinder and a piston, a free exhaust port in the cylinder controlled by the piston, a valve chest having a rectangular 10 valve chamber, inlet passages leading from the valve chamber to the cylinder, a rectangular valve slideable in the valve chamber having actuating and holding surfaces at its ends constantly exposed to pressure fluid, 15 lateral flanges on the valve slideable over the inlet passages to control the admission of pressure fluid into the cylinder, and pressure surfaces on the top of the flanges constantly exposed to pressure fluid for holding the 20 valve firmly seated in the valve chamber.
4. In a fluid actuated rock drill, the combination of a cylinder and a piston, a free exhaust port in the cylinder controlled by the piston, a valve chest having a rectangular 25 valve chamber, inlet passages leading from the valve chamber to the cylinder, a rectangular valve slideable in the valve chamber having actuating and holding surfaces at its ends constantly exposed to pressure fluid, 30 lateral flanges on the valve slideable over the inlet passages to control the admission of pressure fluid into the cylinder, pressure surfaces on the top of the flanges constantly exposed to pressure fluid for holding the valve 35 firmly seated in the valve chamber, a recess in the valve, and a pin in the valve chest extending into the recess to act as a stop for the valve.

In testimony whereof I have signed this
40 specification.

ALBERT R. MACK.
